CLAUDE H. DANIELS, OF NEWTON CENTER, MASSACHUSETTS

BOOT OR SHOE AND METHOD OF MAKING SAME

Application filed March 18, 1930. Serial No. 436,729.

My present invention relates to novel boots or shoes, and includes a novel method of manufacturing the same.

In carrying out my present invention I utilize two vamp pieces, an outside piece and a lining, both of these pieces being preferably of identical size. I preferably utilize leather as the outer vamp piece, and for a lining I utilize a sheet of material of greater toughness and less stretch than the outside vamp piece.

I then coat the entire contacting face of either one or both of said vamp pieces, and subject the same to a pressure operation, which will effectually unite the two vamp pieces into a substantially integral vamp. I preferably also utilize heat during the pressing operation to more fully insure the union of the said two vamp pieces.

As the next step in my novel method, I then subject the entire vamp, in its united condition, to a perforating operation, punching a plurality of substantially equi-sized and substantially equi-spaced apertures throughout substantially the entire area of said vamp. This perforating of the entire area of the vamp would have a weakening effect on the vamp materials, were it not for the fact that I utilize a lining of considerable toughness and little stretch, said lining, nevertheless, being of desired flexibility. Thus, although the vamp is perforated throughout its entire extent, it may be pulled over and lasted without materially distorting the upper materials or the perforations or apertures. This lack of distortion is also due to the fact that the individual perforations are of small individual size, and their aggregate area will, therefore, not materially weaken the vamp or upper materials.

As the next step in my novel process I apply a collar, preferably also of leather, completely around the throat portion of the vamp, securing said collar to said vamp by a single row of stitching, the collar projecting beyond the vamp around the margin of the throat portion.

Thereafter I unite the quarter of the shoe to said collar by a row of stitching extending partially along said collar.

The quarter lining is then united to the quarter, the vamp, and the collar, by a row of stitching extending completely through said lining, quarter, vamp and collar, the quarter lining concealing the row of stitches which unites the quarter to the collar. Thereupon, a beading or trimming is applied over the free edge of said collar along a portion of the throat, and a row of stitching is applied uniting the quarter lining, quarter and beading, and, at the throat portion of the shoe, uniting the quarter lining, beading and collar.

I believe that the steps of the process of shoe manufacture above briefly outlined are novel, as well as the resulting shoe constructed thereby, and have, therefore, claimed the same in this application.

I may also insert, between the two vamp layers, at their toe portion, a toe stiffener, coating one or more surfaces thereto with adhesive, and subjecting the vamp with the toe stiffener therein to the same steps as above enumerated.

I believe that it is novel to adhesively unite a toe stiffener as an integral part of the vamp, and to perforate completely through the toe portion of the vamp, whereat this toe stiffener is located, and have also claimed this feature in the present application.

After the vamp and quarter are united, as above explained, the shoe may be completed in the usual manner, whether by welt or McKay processes.

The above and other objects of the invention, details, and features, will be hereinafter more fully pointed out, described and claimed.

Referring to the drawings, illustrating a preferred embodiment of the present invention,

Fig. 1 is a plan view of the two vamp pieces assembled and coated, and with one layer turned back to illustrate the position of the toe stiffener;

Fig. 2 is a side elevation of the united vamp during the pressure operation;

Fig. 3 is a fragmentary longitudinal sectional view illustrating the perforating operation;

Fig. 4 is a plan view of the completely perforated vamp;

Fig. 5 is a fragmentary plan view of the perforated vamp with the collar stitched thereto;

Fig. 6 is a cross sectional view on the line 6—6 of Fig. 5;

Fig. 7 is a perspective view of the completed shoe;

Fig. 8 is a cross sectional view on the line 8—8 of Fig. 7; and

Fig. 9 is a cross sectional view on the line 9—9 of Fig. 7.

Referring now to the drawings, for a particular description of the invention, and the method of carrying out the same, my novel vamp comprises two layers of material, 1 and 2, these layers being preferably cut to identical size before uniting. The layer 1 is preferably of leather, although it is within the purview of my invention to utilize other materials if desired. The layer 2 is preferably of a material different from the layer 1.

There are several well known textile materials suitable for the lining layer 2, said materials being much tougher and less elastic than the leather utilized in the outside vamp layer 1. The contacting faces of the layers 1 and 2 are then coated with a suitable adhesive 30 as at 3—3, either one or both of said surfaces being thus treated.

If desired, also, a layer 4 may be inserted between the two layers 1 and 2 at their toe portion, this layer 4 being of a suitable material 35 to provide a toe stiffener in the completed shoe. The surfaces of this stiffener layer 4 may be coated with a suitable adhesive, as illustrated at 5, if desired, although the adhesive 3 on the layers 1 or 2 may be sufficient 40 for this purpose.

The adhered layers 1, 2 and 4 are then subjected to a press operation, as between the two presser members 6 in Fig. 2. These presser members 6 are also preferably heated, although this is not essential. The pressing operation will firmly and integrally unite the layers 1, 2 and 4, or the layers 1 and 2, if the stiffener layer 4 is not utilized.

Subsequent to the pressing operation I then 50 subject the united vamp materials to a perforating operation, the die 7 operating in conjunction with the anvil 8 to perforate a mass of fine apertures or perforations 9 completely through the united vamp materials, as 55 well as through the stiffener layer 4. As clearly illustrated in Fig. 4, this mass of perforations extends over the entire area of the vamp materials, even to the edges thereof.

A collar 10 is then united to the vamp along 60 the entire throat margin thereof by a single row of stitching 11. This collar is of sufficient width so that a portion thereof will extend beyond the throat margin, as clearly illustrated in Figs. 5 and 6.

As the next step in my novel process, the

outside quarter 12 is united to the collar 10 by a row of stitching 13, subsequent to which the quarter lining 14 is united to the vamp layers 1 and 2, and collar 10, and, throughout a portion of its extent to the outside quarter layer 12, by a row of stitching 15, this stitching, at the point illustrated by the section line 9—9, extending through the quarter lining 14, outside quarter 12, vamp layers 1 and 2, and collar 10, and at the point illustrated by the section line 8—8, the stitching 15 passes through the strip 16 of the quarter lining, vamp layers 1 and 2, and collar 10.

Subsequent thereto, a beading 17 is affixed to the free edge of the collar 10 by a row of stitching 18, another row of stitching 19 uniting the quarter lining 14 and its strip 16 to the collar 10 and beading 17. Thereafter the thus assembled upper materials will be assembled on a last, and completed in any desired manner, whether welt or McKay, the outsole 20 and heel 21 being applied in the usual manner.

From a glance at Fig. 9 it will be apparent that the row of stitching 13 will be concealed on the interior of the shoe by the quarter lining 14. It will thus be apparent that I have devised a novel process of manufacturing shoes, both in the assembly and perforation of the vamp, and in the method of attaching 95 the vamp and quarter.

The completed shoe manufactured according to this process will be light and yet strong and durable. Also, because of the perforation of the entire vamp, thorough 100 ventilation will be provided, as well as admitting the sunlight directly to the foot of the wearer.

Because of the combination of the two layers 1 and 2 of the vamp materials, the said 105 vamp will not be distorted during pulling over or lasting, the individual size of the perforations 9 being so small that the aggregate thereof has no material weakening effect on the vamp. The vamp, at the toe portion is 110 still further strengthened by the presence of the stiffener layer 4, which will also assist in retaining the shape of the shoe during wear.

While I have necessarily described my 115 present invention somewhat in detail, it will be appreciated that I may vary the size, shape, and arrangement of parts within reasonably wide limits without departing from the spirit of the invention.

My invention is further described and defined in the form of claims as follows:

1. The improved process of shoe manufacture, which includes the steps of adhesively uniting a vamp, toe stiffener, and vamp lining, and thereafter simultaneously perforating a plurality of apertures completely through said three layers.

2. An improved process of shoe manufacture, which includes the steps of adhesively 130

uniting a vamp, toe stiffener, and vamp lining, said toe stiffener being positioned between said vamp and said lining, subjecting said three elements to pressure, and then 5 simultaneously perforating a plurality of apertures completely through said three layers throughout substantially their entire area.

3. The improved process of shoe manufacture, which includes the steps of adhesively 10 uniting a vamp and vamp lining, perforating said vamp and lining with a plurality of apertures throughout substantially the entire area of said vamp, then stitching a collar 15 around the throat margin of said united vamp, a portion of said collar, throughout its entire length, being free of contact with said vamp, and then stitching the outside quarter to said collar adjacent to the open 20 ends of said throat portion.

4. The improved process of shoe manufacture, which includes the steps of adhesively 25 uniting a vamp and vamp lining, perforating said vamp and lining with a plurality of apertures throughout substantially the entire area of said vamp, then stitching a collar 30 around the throat margin of said united vamp, a portion of said collar, throughout its entire length, being free of contact with said vamp, then stitching the outside quarter to said collar adjacent to the open ends of 35 said throat portion, and then stitching the quarter lining to the quarter, vamp and collar adjacent to the open ends of said throat, and to the vamp and collar along the inner 40 throat portion.

5. The improved process of shoe manufacture, which includes the steps of adhesively 45 uniting a vamp and vamp lining, perforating said vamp and lining with a plurality of apertures throughout substantially the entire area of said vamp, then stitching a collar 50 around the throat margin of said united vamp, a portion of said collar, throughout its entire length, being free of contact with said vamp, then stitching the outside quarter to said collar adjacent to the open ends of 55 said throat, and to the vamp and collar along the inner throat portion by a line of stitching located closely adjacent to the line of stitching which secures the collar to the vamp.

6. The improved process of shoe manufacture, which includes the steps of adhesively 60 uniting a vamp and vamp lining, perforating said vamp and lining with a plurality of apertures throughout substantially the entire area of said vamp, then stitching a collar 65 around the throat margin of said united vamp, a portion of said collar, throughout its entire length, being free of contact with said vamp, then stitching the outside quarter to said collar adjacent to the open ends

of said throat portion, and then stitching the quarter lining to the quarter, vamp and collar adjacent to the open ends of said throat, and to the vamp and collar along the inner throat portion, the line of stitching which 70 secures the outside quarter to the collar being concealed on the interior of the shoe by the quarter lining.

7. An improved boot or shoe comprising a 75 vamp consisting of an outside vamp and vamp lining adhesively united and having a plurality of apertures completely therethrough throughout substantially the entire area of said vamp, a collar secured to said vamp along the throat margin thereof, a portion of said collar being free of contact with said vamp, a quarter, stitching uniting said quarter to said collar adjacent to the open ends of said throat, a quarter lining, and a line of stitching uniting said lining to said 80 quarter, vamp and collar adjacent to the open ends of said throat, and to said vamp and collar along that portion of the collar which is free of the quarter.

8. The improved process of shoe manufacture which consists in stitching one edge of a throat collar to the throat margin of a vamp so as to leave the other edge of the throat collar free and extending beyond the throat margin of the vamp, and subsequently stitching a quarter to the free edge portion of said 90 throat collar.

9. The improved process of shoe manufacture which consists in stitching one edge of a throat collar against one face of the throat margin of a vamp so as to have the other edge of the throat collar free and extending beyond the throat margin of the vamp, disposing the edge portion of a quarter in overlapping relation to the throat margin of the 100 vamp against the opposite face of the latter, stitching the free edge portion of the throat collar to the quarter, and stitching through the superimposed edge portions of the vamp, the throat collar and the quarter. 110

10. The improved process of shoe manufacture which consists in stitching one edge of a throat collar against the outer face of the throat margin of a vamp so as to have the other edge of the throat collar free and extending beyond the throat margin of the vamp, disposing the edge portion of a quarter in overlapping relation to the throat margin of the 115 vamp against the inner face of the latter, stitching the free edge portion of the throat collar to the quarter, and stitching through the superimposed edge portions of the vamp, the throat collar and the quarter.

11. The improved process of shoe manufacture which consists in stitching one edge of a throat collar against one face of the throat margin of a vamp so as to have the other edge of the throat collar free and extending beyond the throat margin of the 125 vamp, disposing edge portions of a quarter in 130

overlapping relation to the throat margin of the vamp against the opposite face of the latter and at spaced points, respectively, disposing a beading over the free edge portion of the throat collar between said quarter portions and extending said beading over free edge portions of the said quarter, stitching the free edge portions of the throat collar to the quarter where these parts overlap one another, stitching through the superimposed edge portions of the vamp, the throat collar and the quarter, and stitching the beading to free edge portions of the throat collar and said quarter.

15. 12. The improved process of shoe manufacture which consists in stitching one edge of a throat collar against the outer face of the throat margin of a vamp so as to leave the other edge of the throat collar free and extending beyond the throat margin of the vamp, stitching spaced portions of a quarter to the free edge portion of said throat collar and to the vamp, stitching one edge of a vamp lining strip against the inner face of the throat margin of the vamp between said spaced quarter portions, disposing a beading over the free edge portion of the throat collar between said quarter portions, and stitching through said beading, the free edge portion of the throat collar and the free edge portion of said lining strip.

13. In a boot or shoe, a vamp, a throat collar secured along one edge to the throat margin of said vamp, the other edge portion of said throat collar extending outwardly beyond the throat margin of the vamp, and a quarter secured to the second mentioned edge portion of said throat collar.

14. In a boot or shoe, a vamp, a throat collar secured along one edge to the throat margin of said vamp, the other edge portion of said throat collar extending outwardly beyond the throat margin of the vamp, a quarter having a marginal portion overlapping said throat collar and the throat margin of said vamp, and means securing the said marginal portion of said quarter to the second mentioned edge portion of said throat collar and to the throat margin of said vamp.

15. 15. In a boot or shoe, a vamp including an outside portion, a lining and a toe stiffener between said outside portion and said lining adhesively connected with one another, said vamp being provided with parallel rows of apertures throughout its entire area, the adjacent ends of the apertures in adjacent rows being spaced outwardly from one another whereby there is provided a continuous vamp reinforcing strip between each adjacent pair of rows of said apertures coextensive in length with said rows of apertures.

In testimony whereof, I have signed my name to this specification.
